CLAIM

The ornamental design for protection equipment dispenser, as shown and described.

DESCRIPTION

FIG. 1 is a perspective view of a first embodiment of a protection equipment dispenser design;

FIG. 2 is a front view of a first embodiment thereof;

FIG. 3 is a rear view of a first embodiment thereof;

FIG. 4 is a left-side view of a first embodiment thereof;

FIG. 5 is a right-side view of a first embodiment thereof;

FIG. 6 is a top view of a first embodiment thereof;

FIG. 7 is a bottom view of a first embodiment thereof;

FIG. 8 is a perspective view of a second embodiment of a protection equipment dispenser design;

FIG. 9 is a front view of a second embodiment thereof;

FIG. 10 is a rear view of a second embodiment thereof;

FIG. 11 is a left-side view of a second embodiment thereof;

FIG. 12 is a right-side view of a second embodiment thereof;

FIG. 13 is a top view of a second embodiment thereof; and,

FIG. 14 is a bottom view of a second embodiment thereof.

(Continued)

The broken lines shown represent unclaimed subject matter and form no part of the claimed design.
